UNITED STATES PATENT OFFICE.

ALFRED MONARD, OF PARIS, FRANCE, ASSIGNOR TO SOCIETE L'ASTER, OF PARIS, FRANCE.

LIQUID METER.

Application filed July 12, 1923, Serial No. 651,144, and in France March 29, 1923.

The present invention relates to improvements in liquid meters of the type involving a known driving device actuating a shaft which is interrupted by a clutch device, a cam controlling the device for fastening the valve disposed in the supply conduit being keyed to said shaft outwardly of the clutch device together with a pointer moving over a dial.

The present invention has for its object to provide a liquid meter in which the zero point on the dial is made to coincide with the maximum number of litres which can be supplied; and the lever holding the feed cock open is provided with an arrangement comprising a roller normally moved laterally by a spring in one direction and adapted to be moved in the other direction by means of a lever actuated by the valve stem, whereby the said roller may be moved into and out of the plane of the cam.

Due to my improvements, it is simply necessary to make a single adjustment in order to supply the maximum quantity of liquid in succession as may times as may be desired.

The appended drawings which are given by way of example illustrate a constructional form of meter according to my invention.

Fig. 1 is a perspective view of the apparatus, provided with the special device for fastening the valve.

Fig. 2 is a fragmentary representation of the slide controlling the valve and the said cam.

Fig. 3 is a sectional view of the latter elements in their position immediately before the end of a feeding operation.

Fig. 4 is a like view of the elements after the said operation.

The motion of the driving device *a* is transmitted through the wheels 1, 2 and 3 to the axle 4 which has at the upper part a worm 40 co-operating with a worm wheel 41 keyed to the hollow shaft 9. This latter shaft, which is provided at its outer end with a radially toothed disc 8, rotatably receives the shaft 10 secured to a second toothed disc 12 which is held in engagement with the first-mentioned disc by means of the spring 16. The disc 12 is further provided with the pointer 14 for coaction with the graduations of a dial 15.

A cam disk 13 and a milled operating

head 11 are further mounted upon the shaft 10. In the embodiment according to the invention, a cam 60 is provided upon the said cam disk and is of such size as to occupy but one-half the width of said disk. 60 A valve housing 19 is connected with said pipe *b*, said valve comprising a stem 22 carrying a valve 22^a actuated by a spring 29 and adapted to engage a seat 30. The housing 19 is provided with a connection 65 26 and a conduit for the discharged liquid. In order to lock the valve 22^a of the fuel feed tube *b* in its open position, the stem 22 of said valve has the shoulder D co-operating with a slide 61 horizontally movable 70 by the action of said cam, the said slide being held in contact with the cam.

For this purpose, the said slide is provided with a spring 62 retained by a guiding stop-piece 63; the opposite end of the 75 slide is provided with a fork 66 supporting a shaft 64 upon which is mounted a slide-able roller 65. A spring 67 disposed in the rear of said roller urges the same in the direction of the cam 60 whilst a sleeve-like 80 extension 70 integral with its other face which passes through the adjacent fork 66, permanently bears against the end of a lever 68. This latter which is movable on a vertical axle 69 is so arranged that its outer 85 arm can be actuated by the circular shoulder D of the rod 22.

The operation of the said device is as follows:

When it is desired to measure out the 90 maximum number of litres (shown on the dial) various times in succession, at the start the parts will be in the position of Fig. 4. By pushing upon the stem 22, valve 22^a is opened and the liquid flowing through 95 the driving device *a* rotates the shaft 10 and disk 13 through the members 1, 3, 2, 4, 40, 41, 9, 8 and 12. Upon opening the valve the slide 61 is moved to the right by the spring 62 and it engages below the shoulder 100 D so as to fasten the stem 22 in the open position. As the disk completes a revolution, the cam 60 engages the roller 65 driving it to the left together with the slide 61 as shown in Fig. 3, which compresses the 105 spring 62 and the stem 22 being released, the shoulder D comes into contact with the lever 68 which swings on the axle 69 so as to again bring said roller into the inoperative position of Fig. 4 wherein the spring 67 is 110

compressed. The operations are thus performed in succession without requiring the cam 13 to be turned by hand, and the zero of the dial now coincides with the maximum number of litres to be supplied.

Should it be desired to supply a smaller number of litres than the maximum, it is simply necessary before each operation to pull the shaft 10 outwardly against the tension of the spring 16, and then turn it together with the disk 13 and cam 60 to bring the pointer 14 of the disc 12 by hand in the usual manner opposite the corresponding number of the dial 15. Thus when the valve 22^a is opened the above-described operation will be performed in an analogous manner, the liquid being permitted to flow through the open valve 22^a until, by the rotation of the disk 13, the cam 60 effects displacement of the slide 61 thus releasing the stem 22 and permitting the valve to close.

Obviously, the said apparatus is susceptible of all desired modifications in detail without departing from the spirit of the invention, and in particular, the device may comprise a boss having the same width as the cam, and the roller is herein movable beyond the plane of the said cam.

I claim:

1. In a liquid meter, a valve including a stem adapted to be manually actuated to open the valve, a slide coacting with the valve stem to lock the latter in open position, a rotatable cam, a member on said slide adapted to be engaged and operated by said cam whereby to release the slide,

said member being displaceable laterally to a position out of the path of the cam, a member mounted on said slide actuated by the valve stem during the closing movement of the latter and operating to displace the first mentioned member out of the path of the cam, and means normally tending to return the first mentioned member to cam engaging position.

2. In a liquid meter, a valve including a stem adapted to be manually actuated to open the valve, a slide coacting with the valve stem to lock the latter in open position, a rotatable cam, a driving device for said cam controlled by said valve, a member on said slide adapted to be engaged and operated by said cam whereby to release the slide, said cam operated member being laterally displaceable to a position out of the path of the cam, a member mounted on the slide member actuated by the valve stem during closing movement of the latter and operating to displace the first mentioned member out of the path of the cam, means tending to return the first mentioned member to cam engaging position, a shaft connected with the driving device, means establishing a reliable driving connection between the shaft and the cam, and an indicating device associated with the shaft and cam and including a graduated dial having a zero point coinciding with the maximum quantity of liquid capable of being dispensed by the meter.

In witness whereof I affix my signature.
ALFRED MONARD.
